SYNCHRO FLASH FLOOD SYSTEM

Taz D. Hobbs, Alvin, Tex.

Application May 26, 1950, Serial No. 164,479

2 Claims. (Cl. 315—276)

1

This invention relates to photographic apparatus, and more particularly to a system for obtaining high intensity illumination for photography employing conventional electric lamps.

A main object of the invention is to provide a novel and improved arrangement for obtaining light of photographic intensity from ordinary electric lamps, said system being very simple in construction, involving only a few parts, and being automatic in operation.

A further object of the invention is to provide an improved device for obtaining illumination of photographic intensity from ordinary electric lamps, said device being very inexpensive to construct, being reliable in operation, and involving only a relatively few components.

Further objects and advantages of the invention will become apparent from the following description and claims, and from the accompanying drawing, wherein:

The single figure illustrates schematically the circuit diagram of an improved photographic illumination system constructed in accordance with the present invention.

Referring to the drawing, 11 designates a conventional camera provided with the shutter 12 controlled by a pneumatically actuated trip or release 13. Designated at 14 is a conventional control bulb connected to a Y-shaped fitting 15 at one leg 16 of the fitting. Another leg 17 of the fitting is connected by a hose 18 to the pneumatically operated trip 13. Connected to the stem 19 of the fitting by a hose 20 is a bellows 21, said bellows being adapted to extend its length upwardly, as viewed in the figure, responsive to compression of the bulb 14. Mechanically connected to the top end of the bellows 21 are the respective switch poles 22 and 23. Associated with the switch pole 22 are contacts 24 and 25, the switch pole 22 being normally in engagement with the contact 24, as shown. Associated with the switch pole 23 is a contact 26, the pole 23 being normally out of engagement with contact 26, and the pole 22 being normally out of engagement with the contact 25, said poles being elevated into engagement with the respective contacts 26 and 25 responsive to the expansion of bellows 21 caused by compression of bulb 14.

Designated at 27 are lamp sockets or female receptacles to which lamp sockets may be electrically connected, the elements 27 being connected in parallel to wires 28 and 29. Wire 29 is connected to one of the line wires 30 by a wire 31. The other line wire 32 is connected to the switch pole 22. Designated at 33 is an auto-transformer

2

whose end terminals are connected respectively to the line wire 30 and to the switch contact 26. The inner tap of the winding of the auto-transformer 33 is connected to the switch contact 25 by a wire 34. The upper switch pole 23 is connected by a wire 35 to the wire 28. Designated at 36 is a manually controlled switch pole connected to the wire 35, as shown, and being provided with a contact 37 which is connected to contact 24 by a conductor 38.

In operation, the switch pole 36 may first be closed to energize the lamps connected to sockets 27 at normal brilliance by a circuit which comprises line wire 32, switch pole 22, contact 24, conductor 38, contact 37, switch pole 36, wires 35 and 28, the filaments of the lamps, wire 31 and line wire 30. When the photographic exposure is to be taken, bulb 14 is compressed, thereby extending the bellows 21 and elevating the switch poles 22 and 23 into engagement with the respective contacts 25 and 26. This applies line voltage to the lower portion of the auto-transformer winding by a circuit comprising line wire 32, switch pole 22, contact 25, wire 34, the lower portion of the winding of the auto-transformer 33, and line wire 30. This induces a high voltage across the winding of the auto-transformer 33, said high voltage being applied to the lamps by a circuit comprising line wire 30, the winding of the auto-transformer, switch contact 26, switch pole 23, wire 35, wire 28, the lamp filaments, wire 31 and line wire 30. Simultaneously with the application of high voltage to the lamp filaments, the shutter trip 13 is closed, whereby the shutter 12 is operated, said trip being arranged in a conventional manner to provide a slight time delay in the opening of the shutter to allow the lamps to reach peak brilliance. Due to the exceptionally high voltage applied to the lamps, said lamps provide a much higher brilliance than their normal value. It is therefore possible to employ conventional lamps to obtain the required high illumination for making the photographic exposure.

In the procedure above described, when switch 36 is closed, sufficient illumination is provided to enable the photographers to properly pose their subjects, whereby when bulb 14 is compressed, a proper photographic exposure may be obtained. In the event that the photographer wishes to obtain merely a flash exposure, switch pole 36 is left in the open position and the exposure is taken merely by compressing the bulb 14, whereby the high value of voltage is applied to the filaments of the lamps by the action of the auto-transformer 33.

It will be understood that when the pressure on the bulb 14 is released, reducing the air pressure in the bellows 21, said bellows contracts to its normal position, inasmuch as it is constructed of resilient material or may contain springs, whereby the length of the bellows is normally much less than when air pressure is applied thereto.

While a specific embodiment of an improved apparatus for obtaining light of photographic intensity by the use of conventional electric lamps has been disclosed in the foregoing description, various modifications within the spirit of the invention may occur to those skilled in the art. Therefore, it is intended that no limitations be placed on the invention except as defined by the scope of the appended claims.

What is claimed is:

1. An illuminating system for selectively supplying illumination at different intensities comprising a pair of line wires, a lamp assembly directly connected at one side to one of said line wires, a single pole double throw switch, conductor means connecting the pole of said switch to the other of said line wires, conductor means connecting one terminal of said switch to the other side of said lamp assembly, the pole of said switch being normally closed with said one terminal to apply line voltage to said lamp assembly for providing illumination at a low intensity, an auto transformer having two end terminals and an intermediate terminal, conductor means directly connecting one end terminal of said auto transformer to said one line wire, conductor means connecting the intermediate terminal of said auto transformer to the other terminal of said single pole double throw switch, a single pole single throw switch, conductor means connecting the other end terminal of said auto transformer to the terminal of said single throw single pole switch, conductor means connecting the pole of said single pole single throw switch to said other side of said lamp assembly, said single pole single throw switch being normally open, and manually operated means connected to both of said switches for simultaneously operating the latter to move the pole of said single pole double throw switch from said one terminal to said other terminal and connect said intermediate terminal of said auto transformer to said other line wire to energize said transformer and to close said single pole single throw switch to thereby connect said other end terminal of said transformer to said other side of the lamp assembly and apply the output of said transformer to said lamp assembly for providing illumination at a high intensity.

2. An illuminating system for selectively supplying illumination at different intensities comprising a pair of line wires, a lamp assembly directly connected at one side to one of said line

wires, a single pole double throw switch, conductor means connecting the pole of said switch to the other of said line wires, conductor means connecting one terminal of said switch to the other side of said lamp assembly, the pole of said switch being normally closed with said one terminal to apply line voltage to said lamp assembly for providing illumination at a low intensity, an auto transformer having two end terminals and an intermediate terminal, conductor means directly connecting one end terminal of said auto transformer to said one line wire, conductor means connecting the intermediate terminal of said auto transformer to the other terminal of said single pole double throw switch, a single pole single throw switch, conductor means connecting the other end terminal of said auto transformer to the terminal of said single throw single pole switch, conductor means connecting the pole of said single pole single throw switch to said other side of said lamp assembly, said single pole single throw switch being normally open, manually operated means connected to both of said switches for simultaneously operating the latter to move the pole of said single pole double throw switch from said one terminal to said other terminal and connect said intermediate terminal of said auto transformer to said other line wire to energize said transformer and to close said single pole single throw switch to thereby connect said other end terminal of said transformer to said other side of the lamp assembly and apply the output of said transformer to said lamp assembly for providing illumination at a high intensity, and a third switch interposed in the conductor means between said other side of said lamp assembly and said one terminal of said single pole double throw switch to discontinue operation of said lamp assembly at said low intensity and limit such operation to said high intensity illumination only.

TAZ D. HOEBS.
